UNITED STATES PATENT OFFICE.

HENRY J. UPTON, OF MEDFORD, MASSACHUSETTS.

CAP AND CLIP FOR FOUNTAIN-PENS.

1,288,766.

Specification of Letters Patent. Patented Dec. 24, 1918.

Application filed May 27, 1918. Serial No. 236,688.

To all whom it may concern:

Be it known that I, HENRY J. UPTON, a citizen of the United States, residing at Medford, in the county of Middlesex and State of Massachusetts, have invented certain new and useful Improvements in Caps and Clips for Fountain-Pens, of which the following is a specification.

This invention is a combined cap and 10 clip for fountain pens.

In the drawings,

Figure 1 is a longitudinal sectional elevation on line 1—1 of Fig. 2;

Fig. 2 is an elevation of my combined clip 15 and cap, looking in the direction of arrow in Fig. 1;

Fig. 3 is a section, on line 3—3 of Fig. 1, looking in the same direction as in Fig. 2; and

20 Fig. 4 is a perspective of the clip D.

It has been common practice, in order to provide means to connect a fountain pen with the clothing of the user, when not in actual use in order to prevent loss of the pen, 25 to secure, in some manner, a metallic spring finger or "clip" longitudinally of the cap, so that when the pen was not in use, and the cap was in place over the pen point, the pen might be inserted in a pocket and the 30 cloth of the edge of the pocket inserted between the cap and the spring clip to connect the pen to the clothing of the user.

It is the object of my invention to provide means to connect the clip and the cap 35 which are economical to make, easy and cheap to assemble and secure and effective in result.

In the drawings, A is a cap, the closed end, a, of which has an aperture b formed 40 in it, from one side of the cap, to or beyond the longitudinal axis of the cap. A second aperture c passes from the chamber of the cap into the aperture b.

The clip D has an offset arm, d, pref- 45 erably flat in form and of the same width

as the diameter of the aperture b, which aperture is preferably circular in cross section.

Within the aperture, c, is mounted a pin, p, preferably screw-threaded, which in its advanced or uppermost position impinges upon the offset arm, d, and forces it upward, the edges of arm d biting into the sides of the aperture b, the parts in this manner being frictionally engaged with great firmness. (See Fig. 3.)

It will now be obvious that the clip D thus engaged and secured may be sprung out to receive a part of the cloth of a garment between the clip and the cap and grip 60 the cloth firmly and that the clip will be firmly anchored to the cap so that it cannot be moved in any direction, save that the free end of the clip may be moved outward by virtue of the resiliency of the metal of 65 the clip, to receive the cloth of the pocket and that the assembling and securing of the cap and clip together by means of the pin, p, is both simple, certain and effective.

I have described the preferred form of 70 my device, but it is obvious that the precise form of the apertures and of the pin and lateral arm are not essential elements.

I claim:

In combination, a cap having in the solid 75 closed end of the cap communicating lateral and longitudinal apertures circular in cross-section; a clip, having an offset arm within the lateral aperture which is flat in cross-section and equal in width to the diameter 80 of the lateral aperture; a screw-threaded pin located in the longitudinal aperture; all organized, as described, to cause the screw pin to engage the lateral arm and the edges of the arm to engage the walls of the lateral 85 aperture.

Signed at Boston, Mass., this 21st day of May, 1918.

HENRY J. UPTON.
